UNITED STATES PATENT OFFICE.

JOHN W. MOOSE, OF MOUNT PLEASANT, NORTH CAROLINA.

BASE-BALL BAT.

SPECIFICATION forming part of Letters Patent No. 377,686, dated February 7, 1888.

Application filed September 9, 1887. Serial No. 249,235. (No model.)

To all whom it may concern:

Be it known that I, JOHN W. MOOSE, a citizen of the United States, and a resident of Mount Pleasant, in the county of Cabarrus and State of North Carolina, have invented certain new and useful Improvements in Base-Ball Bats; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved base-ball bat. Fig. 2 is a longitudinal vertical sectional view of the same, and Fig. 3 is a longitudinal vertical sectional view of another form of my bat.

Similar letters of reference denote corresponding parts in all the figures.

My invention has relation to base ball bats; and it has for its object to provide means whereby bats may be strengthened without adding materially to the weight of the same; and it consists in the improved construction and combination of parts of my invention, as will be hereinafter more fully set forth.

In the accompanying drawings, the letter A indicates the body of my bat, having a bore, B, extending throughout its entire length and having its upper and lower ends recessed to form seats C.

D represents the metallic tube secured in the bore of the bat and having its screw-threaded ends projecting slightly beyond the ends of the bat. Although I have shown a tube, a rod may be substituted, if desired.

Concaved caps E are placed in the seats C at the ends of the bat, and have apertures F, through which the screw-threaded ends of the tube project. These caps are formed with countersinks G, which serve as seats for the slightly-concaved nuts, which are screwed upon the ends of the tube, forcing the caps firmly against the ends of the bat and into the seats or recesses thereof. The ends of the tube are then flattened, so as to prevent the nuts from working off.

I have shown in Fig. 3 a slight modification,

which consists in forming the bore tapering, 50 corresponding with the taper of the bat, and of course in this event the rod or tube will be formed tapering, also, to conform with the taper of the bore.

From the foregoing description, taken in connection with the accompanying drawings, the operation and advantages of my invention will be readily understood without requiring further explanation. It will be seen that the body of my bat is not only strengthened by my improvement, but that the ends are protected and prevented from splitting and chipping.

Having thus described my invention, I claim and desire to secure by Letters Patent of the United States—

1. In a base-ball bat, the combination of a bat cored its entire length, with a metallic tube inserted in said core and having its screw-threaded ends projecting slightly beyond the ends of the bat, and apertured caps and nuts for forcing the caps firmly against the ends of said bat.

2. In a base-ball bat, the combination of a bat having a core extending its entire length, seats or recesses formed in the ends of said bat, concaved caps placed in said seats, with a metallic tube inserted in said core and having its screw-threaded ends projecting slightly therefrom and through the apertures in said nuts, and nuts screwed upon the ends of said tube.

3. In a base-ball bat, the combination of a bat having a core extending its entire length, seats or recesses formed in the ends of said bat, concaved caps formed with countersinks placed in said seats, with a metallic tube inserted in said core and having its screw-threaded ends projecting slightly therefrom and through the apertures in the said caps, and slightly-concave nuts screwed upon the screw-threaded ends of said tube and seated in the 90 seats of the concaved caps.

In testimony that I claim the foregoing as my own I have heretunto affixed my signature in presence of two witnesses.

JOHN W. MOOSE.
